UNITED STATES PATENT OFFICE

WILLIAM VENNARD, OF KINGS CROSS, LONDON, ENGLAND

LOOSE-LEAF BINDER

Application filed November 16, 1928, Serial No. 312,798, and in Great Britain August 20, 1928.

The present invention relates to improvements in or relating to loose leaf binders of the kind in which the covers are connected together by thongs on which the sheets are 5 removably mounted, and the thongs are tensioned or relaxed by means of a stretcher bar which is actuated by hand, means being provided for locking the stretcher bar in the position in which it is desired to be set.

10 An object of the present invention is to provide a locking mechanism which is simple in character and by means of which the locking and unlocking is expeditiously carried out.

15 In the drawings:—

Fig. 1 is a plan view of a binder with the covers fully open to show the general arrangement of the invention.

Fig. 2 an under plan view on a larger scale 20 of the locking mechanism in the released position and Fig. 3 a similar view with the locking mechanism in action.

Fig. 4 is a transverse section through the line 4—4 of Fig. 1, but on a larger scale.

25 In the construction illustrated by the drawings the stretcher bar 1 is arranged to slide on a guide member 2 bar and slipper fashion, and means are provided on the stretcher bar for setting up a friction grip between this 30 and the guide-bar so as to produce a clamping lock for locking the stretcher bar in the position in which it is desired to be set.

The friction grip is provided by means of a cam lever grip, the cam 3 being rotatably 35 mounted on the stretcher bar 1, and the actuating arm or lever 4 turning in a plane parallel with and adjacent to the plane of the stretcher bar.

The slide-guide-bar passes through a pair 40 of spaced parallel slides 5 suitably formed or provided on the underside of the stretcher bar intermediately of the ends thereof, and the cam 3 is located in a position to one side of the guide-bar, so that the cam is adapted 45 on rotation to set up a friction grip on the guide-bar. Rotation of the cam is effected by the thumb or finger arm or lever 4 fixed to the axis of the cam from the upperside of the stretcher bar.

50 As shown the cam itself has means for lim-

iting the movement when unlocking. The edge adjacent the lower step of the cam (Fig. 3) is arranged to contact with the guide-bar as shown in Fig. 2 and prevent further movement of the cam when this has been moved to 55 the unlocked position.

The present invention thus realizes a simple, dependable, inexpensive hand operated thong mechanism with a locking action which eliminates the semi-positive character of locking mechanisms which involve the use of springs.

What I claim is:—

1. In a thong loose-leaf binder of the character described, the combination with a 65 stretcher bar for the thongs, of a guide member on which said bar runs, a pivot member extending through the stretcher bar, a cam attached to said pivot member on one side of said stretcher bar, and an actuating arm for 70 said cam attached to said pivot member on the other side of said stretcher bar, said cam cooperating with said guide member to lock the stretcher bar in the position in which it is desired to be set. 75

2. In a loose-leaf binder according to claim 1, a part on said cam contacting with the guide bar for limiting the movement of the cam when unlocking.

In testimony whereof, I affix my signature. 80
WILLIAM VENNARD.
